UNITED STATES PATENT OFFICE.

WILLIAM J. TUCKER, OF NORTON, MASSACHUSETTS, ASSIGNOR TO SAART BROTHERS COMPANY, A CORPORATION OF RHODE ISLAND.

LOOSE-POWDER CONTAINER.

Application filed November 9, 1925. Serial No. 67,827.

To all whom it may concern:

Be it known that I, WILLIAM J. TUCKER, a citizen of the United States, residing at Norton, in the county of Bristol and State 5 of Massachusetts, have invented certain new and useful Improvements in Loose-Powder Containers, of which the following is a specification.

My invention relates to vanity cases or 10 compacts primarily purposed to dispense powder.

The essential objects of my invention are to prevent sifting of the powder at all times; to prevent packing of the powder; 15 to afford means for loosening the powder particles adjacent the perforated plate; to normally maintain the powder pad tightly over the discharge perforations; and to attain these ends in an inexpensive structure.

20 My invention consists in the means and mechanism for producing the results above specified substantially as hereinafter claimed.

In the accompanying drawings illustrating the principle of this invention—

25 Figure 1 is a diametrical central section of a powder container embodying my invention,

Figure 2, a plan of the same in open position showing a portion of the cover broken 30 away,

Figure 3, a perspective view of the pad frame or holder, the pad being removed, and

Figures 4 and 5, top plan view of the 35 perforated plate and the resilient member respectively.

Similar reference numerals indicate similar parts throughout the views.

My receptacle includes a box of any preferred cross sectional outline having a base 40 9 and side 10. To this side is attached by a hinge 11 a hollow cover 12 provided with a cavity 13 to receive the lip 14 of a spring catch 15 operable by a thumb piece 45 16 extending through an opening in the box side. The cover may if desired contain the usual mirror 20, and a pocket 22 for a rouge compact 23 and pad 24.

Concentrically of the box is fixed a tubular member 26. In this instance the latter 50 includes a closed end 27 soldered to the box base 9. An annular spacing member 30 engages the wall 10 and the member 26. It consists of a circular horizontal portion

31, and a vertical portion 32 fixed by solder 55 to the base 9.

The member 26 forms the wall of a pocket 35 in the bottom of which loosely rests a resilient member 36 comprising a circular plate 37 provided with a peripheral series 60 of transversely arcuate upwardly inclined or curved resilient lugs 38.

Resting upon the free ends of the lugs 38, but detached therefrom, is a disk 39 provided with discharge perforations 40. Upwardly indented projections 41 are disposed diametrically opposite each other upon the disk which is slidable and rotatable in the pocket 35 with its periphery in contact with the tubular member 26. It will be understood that the powder to be dispensed is to be located in the pocket 35 between the plate 37 and disk 39. A depression of the latter forces the loose powder up through the perforations 40, but should the powder harden through long disuse or for any other reason the disk 39 may be rotated by manually pressing against the projections 41 in a downward and circular direction to grind 75 the particles away from the hardened 80 powder mass.

A hollow frame 44, as shown in Figure 3, is detachably mounted in the mouth of the pocket and presses the perforated disk against the resilient lugs. It also carries 85 the powder pad or puff 45. In detail this frame comprises a top 46 which forms an annular peripheral rim, and a side 48 terminating in an inturned annular flanged portion 49. The bottom of the frame is 90 therefore open. The top 46 of the frame has a central opening 47 in which fits the flange portion 49 of a lid 50 connected to the top 46 by a hinge member 52. The lid is normally held closed by a latch 54 pivoted on 95 a pin 55 and adapted to slide under a finger 56 raised upon the top. The side 48 frictionally engages the inner surface of the tubular member 26 and may be easily disengaged therefrom for the purpose of recharging by placing a thumb nail below the rim of the top 46 and raising the latter.

The pad 45 is enclosed by the side of the frame and is supported by its flanged portion 49. The lid 50 when closed presses 100 down upon the pad and maintains the latter tightly against the disk 39 and over the perforations thereof so that no powder can

sift therethrough. When returning the frame 44 to its seat after recharging the pocket 35 it is advisable that the cover 50 remain locked upon its enclosed pad to insure that none of the powder that might be accidentally driven up through the perforations and past the pad escape from the frame.

When it is desired to use the container the cover 12 is elevated as well as the lid 50. The pad 45 is then taken in the hand and rubbed over the upper face of the perforated disk 39, which tends to depress the latter against the action of the resilient member and force the loose powder upwardly through the perforations.

I claim:—

1. In an article of the character described, a box provided with a pocket, a cover on the 20 box, a resilient member in the pocket, a perforated disk slidably mounted in the pocket resting on the resilient member, a detachable hollow frame fast in the pocket abutting against the disk, a top upon the 25 frame below the cover provided with an opening, a closure on the top covering the opening, and a pad in the frame below the top engaging the disk.
2. In an article of the character described, 30 a box comprising a base and a side, a tubular member fixed to the base, a resilient member in the tubular member comprising a plate supported by the base and upwardly inclined resilient lugs upon the plate, a disk in the tubular member provided with perforations and engaging the lugs, a hollow frame fast to the end of the tubular member, and a pad in the frame closing the 35 perforations.
3. In an article of the character described, 40 a box, a tubular member attached at one end to the box, a resilient member in the attached end of the tubular member, a disk provided with perforations supported in the tubular member by the resilient member, a detachable hollow frame comprising a side frictionally mounted in the open end of the 45

tubular member and engaging the disk, a top on the frame provided with a central opening, and a peripheral rim on the top 50 overlapping the tubular member.

4. In an article of the character described, a box, a tubular member attached at one end to the box, a resilient member comprising a plate loose in the attached end of 55 the tubular member, and resilient lugs upon the plate within the tubular member, a disk provided with perforations slidably mounted in the tubular member abutting against the lugs, a hollow detachable frame 60 comprising a side frictionally engaging the tubular member and contacting with the disk, a top on the frame provided with an opening, a closure for the opening pivotally mounted on the top, and a pad in the 65 frame engaged by the disk and by the closure.

5. In an article of the character described, a box provided with a pocket, a cover on the 70 box, a resilient member in the pocket, a disk loose in the pocket provided with perforations and resting upon the resilient member, elevations upon the disk, a closed frame seated in the pocket adjacent the disk below the cover, and a pad in the 75 frame resting on the disk and closing the openings.

6. In an article of the character described, a box comprising a base and a side, a tubular member fixed at its lower end to the 80 base and spaced from the side, a spacing member between the tubular member and the side, a cover hingedly connected to the side, a resilient member supported by the base in the tubular member, a disk resting 85 upon the resilient member provided with perforations, a hollow frame detachably engaging the tubular member and the disk, a top upon the frame, and a pad in the frame resting on the disk. 90

In testimony whereof I have affixed my signature.

WILLIAM J. TUCKER.
